UNITED STATES PATENT OFFICE.

ROBERT STIRLING, OF SURREY, ENGLAND.

METHOD AND APPARATUS FOR RAISING LIQUIDS BY COMPRESSED AIR.

No. 857,768.

Specification of Letters Patent.

Patented June 25, 1907.

Application filed June 20, 1905. Serial No. 266,181.

To all whom it may concern:

Be it known that I, ROBERT STIRLING, of The Anchorage, Dormans Park, Surrey, England, engineer, have invented a certain 5 new and useful Improved Method and Apparatus for Raising Liquids by Compressed Air, of which the following is a specification.

This invention relates to apparatus for raising liquids by compressed air.

10 The object of the invention is to provide an apparatus which will work efficiently and economically in deep wells generally, and in wells where the surface of the liquid is at a considerable depth below the surface of the 15 ground and the depth of the liquid small in comparison therewith.

Various means have been tried with a view 20 to improving the efficiency of liquid-raising apparatus of the air-lift type. It has heretofore been proposed to so form the air and liquid inlets to the discharge pipe as to obtain, under given conditions, the maximum 25 velocity in the discharge pipe due to the external head of the liquid. In such apparatus 30 the entering liquid was frequently introduced at a velocity which was 8 or 10 times as great as the normal velocity of the mixture just above it. This apparatus, while an improvement upon the older types of apparatus 35 wherein the entering liquid had a very low speed, did not satisfactorily solve the problem. It has hitherto been found that 60 per cent. or 70 per cent. submergence was necessary for the best results, and when this 40 submergence was not attainable, or, in other words, when the ratio of the distance of the nozzle below the surface of the liquid was to the distance from the surface of the liquid to the discharge much less than the ratio of 9 to 6, the well was pronounced unsuitable for air-lift pumping.

Now I have discovered that the efficiency 45 of air-lift apparatus can be greatly improved, and a steady and regular discharge obtained, by causing the liquid to enter the rising or discharge pipe at a velocity which is approximately equal to that of the mixture of liquid and air in the discharge pipe immediately 50 above the liquid inlet or inlets. The ideal 55 conditions are attained when the velocity of the entering liquid is precisely the same as that of the mixture above it, but I have found in practice that these conditions may be somewhat widely departed from while 60 still obtaining to a greater or less degree the advantages of my invention. The speed of

the entering liquid may be somewhat below that of the mixture, or it may be considerably above the speed of the mixture and important results still be obtained. I have 60 found in practice that the velocity of the entering liquid may be 2 or 3 times that of the mixture with good results, while if raised materially beyond this speed the efficiency of the apparatus decreases, while with the inlet 65 speed 8 or 10 times the speed of the mixture, as in the apparatus hereinbefore referred to, a considerable drop in efficiency takes place. These variations in relative speed which lie within the scope of my invention are intended 70 to be included, for the want of a better term, in the phrase "approximately equal to the velocity of the mixture", or any phrase of like import used herein. Generally I have found that satisfactory results are obtained 75 when the parts are so proportioned that the velocity of the entering liquid is not greater than that which would be due to a head of 10 per cent. of the submergence. In other words, the entering liquid is given the ve- 80 locity which it would have if permitted to flow unimpeded into a pipe the end of which was submerged 1/10 of the actual degree of submergence in practice. Under these conditions a considerably greater speed is given 85 to the liquid than to the mixture. This is advantageous, as the level of the water in a given well is apt to vary greatly, and when at its lowest point the inlet speed is substantially reduced. Such reduction should not 90 carry it materially below the speed of the mixture.

An important feature of my invention is that the submergence of less than 50 per cent. can be worked with greater advantage, the 95 apparatus being adapted to be placed below the level of the liquid at a depth which bears a ratio to the depth from the surface of the liquid in the well to the point of discharge of less than 4 to 6. Thus a saving is effected 100 in the material of the piping, in the friction due to length of piping, and to less air pressure being necessary as the amount of submergence is less, and wells hitherto unsuited for air-lift pumps can be worked by this 105 means. By my invention the slip of air through the liquid is reduced to the minimum, and waste of energy resulting from change of speed is obviated.

In practicing my invention I provide a 110 nozzle or nozzles for admitting the liquid in suitably determined volume and velocity to

the discharge pipe, rising pipe or the like from the tube, well or other source, this nozzle or nozzles being adapted to restrict the flow of the liquid to be raised; not, as heretofore, with the object of obtaining the maximum velocity due to the external head, but having its passage or passages through which the liquid passes to the discharge pipe of such dimensions as to obtain a velocity of liquid in and through the nozzle or nozzles equal to, or approximately equal to, the initial velocity of the mixture of liquid and air in the discharge pipe immediately above the nozzle or nozzles. In other words, the sectional area of the liquid inlet passage or passages in the nozzle or nozzles bears the same or approximately the same proportion to the area of the discharge pipe, rising pipe or the like as the volume of liquid passing through the nozzle or nozzles in a given time bears to the volume of air and liquid passing through the discharge pipe or the like immediately above the nozzle or nozzles in that time.

The compressed air is admitted in the usual or any convenient way to the liquid in the discharge pipe or the like, above the nozzle or nozzles through which the liquid enters. The passage or passages above the nozzle or nozzles for the admission of the compressed air should be of such area that little or no resistance is presented to the entering air.

Referring now to the drawings:—Figure 1 is a general view of one form of apparatus made in accordance with this invention, in which the air supply pipe is outside the discharge pipe. Fig. 2 is a section of the apparatus showing the air inlet and one liquid inlet nozzle. Fig. 3 is a general view of a modified form of apparatus in which the air supply pipe is disposed outside the discharge pipe, Fig. 4 is a section showing an air inlet and one liquid inlet nozzle adapted for use with the general arrangement shown in Fig. 3. Fig. 5 is a sectional plan thereof. Fig. 6 is a general view of a modified form of apparatus in which the air supply pipe is disposed inside the discharge pipe. Fig. 7 is a section showing the air inlet and the liquid inlet comprising several nozzles adapted for use with the general arrangement shown in Fig. 6. Fig. 8 is a sectional plan thereof. Fig. 9 is a section showing the construction of Fig. 2, with the tapered portion omitted.

a is the well in which the apparatus is disposed, *b* is the air supply pipe, *c* the discharge pipe, *d* the liquid inlet and comprises one or more nozzles, *e* the air inlet and *f* the liquid supply pipe.

In operation, the air is forced down on to the surface of the liquid, and the pressure thereon increases until the level of the liquid is depressed sufficiently to enable the air to get to the air inlet or inlets above the nozzle.

The air then enters below the column of liquid in the discharge pipe, which is thus

partly aerated and discharged. The air continues to enter the discharge pipe, and owing to the relative sectional areas of the nozzle inlet and the discharge pipe, the quantity of liquid entering the discharge pipe through the nozzle or nozzles is automatically regulated by the weight of the aerated column in the discharge pipe to an extent such that the velocity of this inflow is equal to or approximately equal to the velocity of the aerated liquid in the discharge pipe immediately above the nozzle or nozzles, that is to say, above the tapered portion *k*. The inlet area of the nozzle or nozzles is proportioned to this quantity which is predetermined, and can be readily calculated by known methods and formulæ used in designing air lift pumping apparatus, taking into account the quantity of liquid which can be economically discharged through a pipe of given area, and the ratio between the quantities of air and liquid depending on the height of lift and the depth of submergence. As the inlet is restricted so that the liquid enters the discharge pipe at the same or approximately the same velocity as the initial velocity of the mixture of air and liquid and as the volume is such that it is sufficiently lightened to form a rising column by the entering air then slip of the air through the liquid is avoided and there is practically no waste of energy due to change of speed and the efficiency of the apparatus is established.

The proportions just indicated may be varied considerably without departing from the invention. Preferably the velocity of the incoming liquid is exactly that of the rising mixture, but as the depth of submergence is a factor in the velocity of the entering liquid, and as the height of the water in most wells and hence the degree of submergence is variable, such precise velocities cannot in most cases be attained. Preferably the parts are so proportioned that the speed of the liquid and mixture are equal at the low-water point of the well, so that when the water is above this level the speed of the liquid becomes greater than that of the mixture. In most cases the variations can be provided for by proportioning the nozzle so that the velocity of the liquid is not greater than that which would be due to a head of 10 per cent of the submergence.

In the form shown in Figs. 1 and 2, the discharge pipe *c* is disposed concentrically within the compressed air pipe *b* and only one nozzle is used in the air inlet *d*. The pipes *b* and *f* are connected by a socket *g* provided with a ledge *h* adapted to support the discharge pipe *c* provided with the air inlet *e* and the liquid inlet *d* in such a way that communication between the pipes *f* and *c* can only take place through the nozzle *d*. *j* is a ring of suitable material disposed on the ledge *h* so as to make this tight joint.

k is a passage at the foot of the pipe *c* and the air inlet *e* which is connected to the air pipe *b* by several small holes, is of annular form and is directed upwardly into the passage *k*.

5 This passage *k* is for the purpose of providing an easy flow into the discharge pipe *c*.

In the form shown in Figs. 3 and 4 and 5 the discharge pipe *c'* is outside and independent of the air pipe *b'*. The nozzle *d'* is disposed in the socket *g'* and is surrounded by the upwardly directed air inlet *e'* which is connected to the air pipe *b'* by a passage *m* in the socket *g'*.

10 In the form shown in Figs. 6, 7 and 8 the air pipe *b''* passes concentrically down the discharge pipe *c''* and terminates in a head adapted to fit tightly in the pipe *c''* by means of a band *n* of any suitable material. The 15 air inlet is shown at *e''*. The liquid inlet *d''* comprises several nozzles which are carried by the head and open into the annular passage *k''* at the foot of the discharge pipe *c''*, the combined area of said nozzles being equal 20 to the area of the single nozzle proportioned as above described. Similarly several nozzles may be substituted for a single one in the liquid inlets of the forms shown in Figs. 1 to 25 5, the total area of the inlet always being proportioned as above described.

30 In each of the forms hereinbefore referred to there is provided a tapering portion such as *k* *k''* to permit an easy flow into the discharge pipe. Such passage is not necessary and may be omitted, as is shown in Fig. 9, which is in other respects substantially like the form shown in Fig. 2.

What I claim and desire to secure by Letters Patent is:—

40 1. In the raising of liquids by compressed air wherein a current of air is introduced into a discharge pipe which is in communication with the liquid below the level of the latter the method which consists in introducing the liquid into such pipe at approximately the same velocity as that attained by the upwardly moving mixture of liquid and air immediately beyond the point of introduction of said liquid.

45 2. In the raising of liquids by compressed air wherein a current of air is introduced into a discharge pipe which is in communication with the liquid below the level of the latter, the method which consists in introducing the liquid into such pipe through a nozzle, the sectional area of which is so restricted with relation to that of said pipe at a point immediately above such nozzle that the velocity of said liquid passing said nozzle is approximately equal to that of the mixture of air and liquid passing such point.

50 3. The method of raising liquid which consists in submerging the end of a pipe in such liquid, introducing a current of air thereinto at a point below the surface thereof, and re-

65 stricting the inflow of liquid into such pipe so

that its velocity is approximately equal to that of the upwardly moving current of air and liquid.

4. In an air lifting apparatus for liquids, a 70 discharge pipe, an air inlet thereto, and a liquid inlet thereto, the cross sectional area of said liquid inlet and said discharge pipe being so proportioned that the fluid passing through said liquid inlet and that portion of 75 said pipe immediately beyond the same shall move at approximately the same velocity.

5. In an air lifting apparatus for liquids, a 80 discharge pipe, an air inlet thereto, and a nozzle adapted to introduce the liquid into 85 such pipe, said pipe and nozzle having their cross-sectional areas so proportioned that the fluids passing through said nozzle and that portion of said pipe which is immediately beyond the same shall move at approximately 85 the same velocity.

6. In an apparatus for raising liquid by compressed air wherein a current of air is introduced into a discharge pipe which is in communication with the liquid below the level of the latter, a discharge pipe so proportioned with relation to the liquid inlet that the liquid introduced into such pipe shall move at approximately the same velocity as that attained by the upwardly moving 95 mixture of liquid and air immediately beyond the point of introduction of the liquid and air.

7. In the raising of liquids by compressed air wherein a current of air is introduced into 100 a discharge pipe which is in communication with the liquid below the level of the latter the method which consists in introducing the liquid into such pipe at a velocity approximately equal to that of the mixture of liquid 105 and air above the liquid inlet, but not greater than that due to a head of 10% of submergence.

8. In the raising of liquids by compressed air wherein a current of air is introduced into 110 a discharge pipe which is in communication with the liquid below the level of the latter the method which consists in introducing the liquid into such pipe through a nozzle the sectional area of which is so restricted with relation to that of said pipe at a point immediately above such nozzle that the velocity of 115 said liquid passing said nozzle is not greater than that due to a head of 10% of submergence.

9. The method of raising liquid which consists in submerging the end of a pipe in such liquid, introducing a current of air thereinto at a point below the surface thereof, and restricting the inflow of liquid into such pipe so 120 that its velocity is not greater than that due to a head of 10% of submergence, whereby the velocity of the entering liquid approximates that of the mixture above it.

10. In an air lifting apparatus for liquids, a 130

discharge pipe, an air inlet thereto, and a liquid inlet thereto, the cross-sectional areas of said liquid inlet and said discharge pipe being so proportioned that the fluids passing through said liquid inlet and that portion of said pipe immediately beyond the same shall move at a velocity not greater than that due to a head of 10% of submergence.

11. In an air lifting apparatus for liquids, 10 a discharge pipe, an air inlet thereto, and a nozzle adapted to introduce the liquid into such pipe said pipe and nozzle having their cross-sectional areas so proportioned that the fluids passing through said nozzle and that portion of said pipe which is immediately beyond the same shall move at a velocity not greater than that due to a head of 10% of submergence.
12. In an apparatus for raising liquid by 20 compressed air wherein a current of air is introduced into a discharge pipe which is in communication with the liquid below the level of the latter, a discharge pipe so proportioned with relation to the liquid inlet 25 that the liquid introduced into such pipe shall move at a velocity not greater than that due to a head of 10% of submergence.

13. In the raising of liquids by compressed air wherein a current of air is introduced into 30 a discharge pipe which is in communication with the liquid below the level of the latter, the method which consists in introducing the liquid into such pipe through a plurality of nozzles the sectional area of which is so restricted with relation to that of said pipe at a point immediately above such nozzles that the velocity of said liquid passing said nozzles is approximately equal to that of the mixture of air and liquid passing such point.
14. In an air lifting apparatus for liquids, 40 a discharge pipe, an air inlet thereto, and a plurality of nozzles adapted to introduce the liquid into such pipe said pipe and nozzles having their cross-sectional areas so proportioned that the fluids passing through 45 said nozzles and that portion of said pipe which is immediately beyond the same shall move at approximately the same velocity.
15. In the raising of liquids by compressed 50 air wherein a current of air is introduced into

a discharge pipe which is in communication with the liquid below the level of the latter, the method which consists in introducing the liquid into such pipe through a plurality of nozzles the sectional area of which is so restricted with relation to that of said pipe at a point immediately above such nozzles that the velocity of said liquid passing said nozzles is not greater than that due to a head of 10% of submergence.

16. In an air lifting apparatus for liquids, a discharge pipe, an air inlet thereto, and a plurality of nozzles adapted to introduce the liquid into such pipe said pipe and nozzles having their cross-sectional areas so proportioned that the fluids passing through said nozzles and that portion of said pipe which is immediately beyond the same shall move at a velocity not greater than that due to a head of 10% of submergence.

17. The combination with a well or the like, of an air lifting apparatus having a liquid inlet at a predetermined depth of submergence, and a discharge pipe for the mixture of air and liquid beyond said inlet, said inlet and discharge pipe immediately beyond said inlet being so proportioned with relation to the depth of submergence that the incoming liquid flows at approximately the same velocity as the mixture in such portion of the discharge pipe.

18. The combination with a well or the like, of an air lifting apparatus having a discharge pipe, and a nozzle adapted to introduce liquid into such pipe, such nozzle being arranged at a predetermined depth of submergence, said pipe and nozzle having their cross-sectional areas so proportioned with relation to the depth of submergence that the incoming liquid flows at approximately the same velocity as the mixture of air and liquid in said discharge pipe immediately beyond said nozzle.

In witness whereof, I have hereunto signed my name in the presence of two subscribing witnesses.

ROBERT STIRLING.
